FISHING LURE

Harold C. Starkey, Arcata, Calif.

Application October 26, 1949, Serial No. 5,722

Term of patent 14 years

(Cl. D31—4)

To all whom it may concern:

Be it known that I, Harold C. Starkey, a citizen of the United States of America, residing at Arcata, county of Humboldt and State of California, have invented a new, original, and ornamental Design for a Fishing Lure, of which the following is a specification, reference being had to the accompanying drawing, forming a part thereof wherein—

Figure 1 is a top plan view of a fishing lure, showing my new design.

Figure 2 is a perspective view of the fishing lure looking at the upper or top side thereof.

Figure 3 is a perspective view of the fishing lure looking at the lower or bottom side thereof.

Figure 4 is a sectional view taken on a plane indicated by the line 4—4 of Figure 1, and

Figure 5 is a sectional view taken on a plane indicated by the line 5—5 of Figure 1.

I claim:

The ornamental design for a fishing lure, as shown.

HAROLD C. STARKEY.
